UNITED STATES PATENT OFFICE.

JOHN A. CLARK, OF LOS ANGELES, CALIFORNIA, ASSIGNOR OF ONE-HALF TO GEORGE I. DANIELS, OF LOS ANGELES, CALIFORNIA.

STAND.

No. 909,547.

Specification of Letters Patent. Patented Jan. 12, 1909.

Application filed March 10, 1908. Serial No. 420,148.

To all whom it may concern:

Be it known that I, JOHN A. CLARK, a citizen of Canada, residing at Los Angeles, in the county of Los Angeles and State of 5 California, have invented new and useful Improvements in Stands, of which the following is a specification.

This invention relates more particularly to telephone stands designed for public use 10 and provided with advertising spaces conveniently and conspicuously arranged, and it consists in a novel arrangement of the stand and the telephones thereon so that they may be moved to and from the stand 15 and the flexible connecting cords taken care of so that they do not become entangled.

This stand is adapted to be placed in a public place, being provided with advertising spaces for public displays. However 20 these spaces may be adapted for other uses and the stand designated for private use, such as for a house or office, the spaces being preferably adapted to receive cards or other memoranda which is of immediate use in 25 proximity to the telephones.

I accomplish the above by means of the device described herein and illustrated in the accompanying drawings, in which:—

Figure 1 is a front elevation of my im- 30 proved telephone stand with parts in section. Fig. 2 is a sectional side elevation of the same.

In the preferred construction of the stand, as illustrated in the drawings, I employ a 35 suitable base 5, which may be of any desired configuration or design. Mounted on base 5 is a hollow column or support 6, illustrated as square in cross section, and supporting a table or desk top 7. This top is provided 40 with a rear vertical panel 8 and with side triangular vertical panels 9, a sloping display board 10 being mounted on panels 8 and 9 so that its surface, or the display cards thereon, may be conveniently viewed by a 45 person in front of the stand. This display board extends around and behind top 7 so that an open space is left for the placement of telephones 11 on the top, this space being surrounded by any advertisements which 50 may be placed upon the display boards. For this purpose the display board is divided into a plurality of separate compartments 13 of suitable size for the reception of display cards, the cards being preferably covered by 55 a plate of glass (not shown). These spaces

may be adapted for the reception of memoranda, such as business or personal cards or cards bearing telephone numbers. On the front face of rear panel 8 a small compartment 14 is formed which is useful for the 60 reception of papers, telephone directories or similar articles. The front face of front wall 15 of this compartment is divided into spaces adapted to receive display cards or similar articles. 65

In the use of this stand I employ the form of telephone commonly known as a "desk telephone" and the bell box 16 may be conveniently mounted on a wall adjacent the stand. Connecting cord 17 passes into hollow support 6 through an aperture 18 and hangs downwardly in the support and then passes upwardly through an aperture 19 in top 7 to be connected to telephone 11. A small weight 20 is provided with a pulley 21 70 and this pulley hangs directly on cord 17 so as to hold it taut within the support, as shown in Fig. 2, and to draw it into the support when telephone 11 is moved towards the stand. By means of this construction it will 75 be seen that the telephone may be removed to some distance from the stand, weight 20 moving upwardly in the hollow support. Upon the telephone being moved towards the stand weight 20 moves downwardly and draws the 80 cord into the support again. 85

From the foregoing description it will be observed that I have provided a stand which is particularly adapted for public telephone use in that it conveniently contains and displays information which is of direct value and convenience to a user of a public telephone, the arrangement of the connecting cords providing means whereby a user of the telephone may move away from the stand to 90 a convenient position to use the telephone more or less privately. 95

Having described my invention, what I claim as new and desire to secure by Letters Patent is:—

1. A telephone stand, comprising a hollow supporting member, a table top mounted on said supporting member, said top adapted to support a telephone, the connecting cord to said telephone passing into said supporting member, and yielding means to hold the connecting cord in said supporting member. 105

2. A device of the class described, comprising a hollow support, a telephone resting on said support, the flexible connecting 110

cord for said telephone passing into said hollow support, and means to normally hold the cord in said support.

3. A telephone stand, comprising a hollow support, a table top mounted on said support, said table top being provided with advertising spaces, and being adapted to support a telephone, the flexible connecting cord for said telephone passing down through said

support, and a weight adapted to hold the cord in said support.

In witness that I claim the foregoing I have hereunto subscribed my name this 29th day of February, 1908.

JOHN A. CLARK.
